UNITED STATES PATENT OFFICE.

ZALKIND ANSHEN, OF BOSTON, MASSACHUSETTS, ASSIGNOR TO HIMSELF AND HENRY MORRIS, OF BOSTON, MASSACHUSETTS, COPARTNERS DOING BUSINESS AS BOSTON JEWELRY MANUFACTURING COMPANY.

DESIGN FOR A CROWN SETTING FOR ARTICLES OF JEWELRY.

Application filed July 14, 1922. Serial No. 3,085. Term of patent 3½ years.

To all whom it may concern:

Be it known that I, ZALKIND ANSHEN, a subject of the Government of Russia, residing at Boston, county of Suffolk, State of Massachusetts, have invented a new, original, and ornamental Design for Crown Setting for Articles of Jewelry, of which the following is the specification, reference being had to the accompanying drawing, forming part hereof.

Fig. 1 is an illustration in side elevation of a crown setting embodying the design of this invention,

Fig. 2 is an illustration similar to Fig. 1, showing the design viewed at right angles to the view shown in Fig. 1.

Fig. 3 is a top plan view of the design as shown in Figs. 1 and 2.

Fig. 4 is a bottom plan view of the crown setting.

I claim:

The ornamental design for a crown setting for articles of jewelry as shown.

ZALKIND ANSHEN.
